Inventor:

Othniel F. Tripp

UNITED STATES PATENT OFFICE.

OTHNIEL F. TRIPP, OF BATTLE CREEK, MICHIGAN.

IMPROVEMENT IN KNITTING-MACHINES.

Specification forming part of Letters Patent No. 152,021, dated June 16, 1874; application filed February 23, 1874.

To all whom it may concern:

Be it known that I, OTHNIEL F. TRIPP, of Battle Creek, county of Calhoun and State of Michigan, have invented an Automatic Knitting-Machine Needle-Shifter, of which the following is a specification:

The object of this invention is to provide a mechanical means for positively depressing the projecting portions of the needle-shanks in their grooves below the surface of the bed-plate, so as to render them temporarily inoperative, and again elevating them into working position, either singly, collectively, or alternately, without disturbing the relative position of their hooks.

The invention consists in the following devices: First, a lever needle-shifter, A, having a needle-holding clamp or arm, G; secondly, a reversing rotary shaft, B, provided with adjustable shifting cam-wheels C; thirdly, an alternating driving-wheel, D, operated by a self-adjusting arm or stop, E, all constructed as hereinafter described, reference being had to the accompanying drawings forming a part of this specification, in which—

Figure 1 gives a perspective view of the invention adjusted to a transverse section of a needle-bed; and Figs. 2, 3, and 4 show the cam-wheels, rotary shaft, and needle-shifter separately and in detail.

A, in Fig. 4, represents the lever needle-shifter, by which the needle H is positively depressed and elevated in its groove alternately. It consists of a flat bar, F, provided with a needle-holding arm or clamp, G, which projects over the bar of the needle, depressing it whenever the bar F is lowered. The bar F extends the entire length of the groove under the needle, and is also provided with a slot or socket, P, for the reception of the cam V, by which it is operated. B is a reversing rotary shaft, supported in any suitable manner, and provided with grooves and stops j, j, and a pinion, K. The grooves and stops j, j are for the purpose of receiving and holding the inner end of the key M. C is an adjustable cam-wheel, provided on one side with a cam, V, and on the other with a radial and circular groove, in the former of which works a movable key or bar, M, for the purpose of adjusting the wheel upon the shaft, and in the lat-

ter is a spring, N, which bears upon the key M, to prevent its accidental displacement. O, Fig. 2, is a friction-spring, bearing, for a similar purpose, upon the side of the wheel C. D, Fig. 1, is an alternating driving-wheel, having shifting pins or bars on one side, and a ratchet on the other. E is a self-adjusting arm or stop, provided with a spring, Q, and attached to the carriage. (Not shown in the drawing.) The gib R has a groove cut in its under side, and the needle-bed S has a corresponding groove, T, directly beneath it, in which the needle-holding arms G of the needle-shifters operate. The needle-bed S is provided with transverse grooves of sufficient depth to receive and allow the operation of the needles and shifters. In adjusting these devices to a knitting-machine—the Lamb machine, for example—the self-adjusting arm E may be suitably attached to the reciprocating carriage, so that the pointed end of the arm shall strike a pin of the driving-wheel, D, propelling it forward and around by degrees. As the carriage recedes the arm is struck by the pin back of it, swinging the point upward until past the pin, when it is again set in position by the spring D. The bevel-gear of the driving-wheel Q, acting upon the pinion K, turns the shaft B, which motion, by means of the cam-wheels and levers, serves to depress and elevate the projecting shanks of the needles. The relative position of the cams may be reversed by the use of the keys M. Thus, partially drawing one of the keys detaches that cam-wheel from the shaft, so that the cam remains stationary while the shaft revolves, operating other needles, while this one remains inoperative; and by pressing back the key while the shanks are below the surface they are depressed or elevated together. Again, drawing one of the keys when the shank is below the surface of the bed, and pressing it back when another is in working position above, both are removed in opposite directions at the same time. Also, by placing the finger against the serrated or milled edges of the cam-wheels and turning them backward and forward, the needle-shanks are raised and lowered independently of the motion of the shaft B. When it is desired to do plain knitting the motion of the shaft B may be sus-

pended by simply pushing up the arm E in its slot until it does not engage with the driving-wheel D.

By means of this invention the operator is enabled to produce with great rapidity the double mittens and gloves, such as are knit by hand, either striped or plain, completing them in the machine; also, an almost endless variety of plain and fancy knitted fabrics, either single, double, or overshot.

I reserve the right to so vary this device as to adapt it to a circular as well as straight machine, so long as I confine myself to means substantially equivalent—for instance, by dispensing with the driving-wheel D and arm E, and operating the needle-shifter by means of longer keys and deeper grooves in the cam-wheels C, acted upon by a cam or cams suitably attached to the carriage or cylinder of such machines.

I claim as my invention—

1. The bed-plate S, provided with the groove T, and the gib R, correspondingly grooved on the under side, in combination with the needle-shifter A, substantially as and for the purpose described.
2. The combination, in a knitting-machine, of the lever needle-shifters A and adjustable lever shifting cam-wheels C, substantially as described.
3. The self-adjusting arm E and driving-wheel D, with the shaft B, in combination with the needle-shifters A and cam-wheels C, substantially as described.

OTHNIEL F. TRIPP.
